UNITED STATES PATENT OFFICE.

EDWARD J. GALLAGHER, OF INTERNATIONAL FALLS, MINNESOTA.

WIND-MOTOR.

1,248,305.

Specification of Letters Patent.

Patented Nov. 27, 1917.

Application filed April 5, 1916. Serial No. 89,199.

To all whom it may concern:

Be it known that EDWARD J. GALLAGHER, a citizen of the United States, residing at International Falls, in the county of Koochiching and State of Minnesota, have invented new and useful Improvements in Wind-Motors, of which the following is a specification.

This invention relates to fluid actuated means for rotating a movable element of an electric generator and has for its primary object to provide a construction directly coupled to the movable element so as to minimize the number of parts required.

An object of the invention is to provide means for directing a fluid toward a propeller directly coupled to the movable element of the generator in such a manner as to properly take care of the shifting of the natural direction of movement of the fluid.

Another object of the invention is to provide simple means for completely cutting off the flow of fluid toward the propeller.

A further object of the invention is to so construct the apparatus that a single element may be moved to a position to simultaneously cut off a number of independent streams of fluid moving toward the propeller.

With these and other objects in view, the invention consists in the construction, combination and arrangement of parts as will be hereinafter more fully described, illustrated in the accompanying drawings, and pointed out in the claims hereunto appended.

In the drawings:

Figure 1 is a side elevation of the complete apparatus.

Fig. 2 is a top-plan view thereof.

Fig. 3 is a vertical sectional view of the propelling mechanism, showing a conventional representation of the generator.

Fig. 4 is a horizontal sectional view taken midway of the generator 8 in Fig. 3.

Fig. 5 is an enlarged vertical sectional view of the generator and its associated parts.

Fig. 6 is a sectional view on the line 6—6 of Fig. 5.

Figs. 7, 8 and 9 are detailed sectional views.

Figs. 10 and 11 are detailed views of the mechanism for controlling the flow of fluid.

Referring to the drawings:

The numeral 1 designates a frame upon the upper portion of which is mounted a bearing block 2 formed with a recess 3. Mounted in the recess 3 is a flange 4 formed on the cone bearing 5. This cone bearing 5 encircles the hollow shaft 6 of the armature 7 of the generator 8.

The field poles 9, the movable element of the generator, are secured to a frame 10. The top and bottom portion of the frame 10 has secured thereto bearing collars 11 that bear upon the ball bearings 12 which in turn bear upon the heretofore mentioned cone bearing 5 and a cone bearing 13 arranged at the upper end of the shaft 6. A cap 14 prevents moisture from gaining access to the bearings and to the armature and field poles.

For accurately controlling the strength of the field circuit, I provide a resistance 15 arranged in series with the field circuit by means of the slip rings 16.

I will now describe the propelling mechanism for the generator which in this particular instance is illustrated as a wind-mill, but I wish it to be understood that with very slight changes, the mechanism may be driven by a liquid.

Detachably secured to the frame 10 is a ring 17 that supports an annular series of vanes 18, the latter increasing in width from their top edges to their bottom edges and slightly curving in a transverse direction.

Encircling the vanes 18 of the propeller is an upper annular plate 19 and a lower annular plate 20, spaced apart vertically so as to form a chamber 21, through which the fluid passes that actuates the vanes of the propeller.

For dividing the fluid into a number of streams and to direct the streams in their most advantageous direction toward the vanes 18, I provide an annular series of deflectors 22. Each deflector has one edge por-

tion formed into a sleeve 23 while that portion adjacent to the vanes 18 is given an arcuate shape as illustrated at 24 for the purpose of deflecting the fluid in a direction to properly strike the vanes 18.

For increasing the efficiency of the apparatus, I mount in the plates 19 and 20 bolts 25 that receive the sleeves 23 for allowing the deflectors to have a swinging movement the amount of which being governed by additional bolts 26 also mounted in the plates 19 and 20.

I will now describe the control mechanism for regulating the amount of fluid passing by the deflectors and acting upon the vanes 18. This mechanism comprises a ring 27 permanently secured to the block 2, while a ring 28 of a greater diameter than the ring 27 is mounted for movement by being flexibly connected to the ring 27 by the annular strip of flexible material 29. The width of the strip 29 is such that when the ring 28 is raised a pre-determined distance above the ring 27 the passage of fluid from the vanes 18 is obstructed and this amount of obstruction depends entirely upon the amount of movement of the ring 28. For moving the ring 28 I provide link mechanism 30 comprising a U-shaped rod 31 having its extremity connected to the ring 28 and its intermediate portion formed into a ring 32, encircling the shaft 6. The rod 31 receives its reciprocatory motion from the lever 33 pivoted as illustrated at 34 and having one extremity forked and engaging the ring 32 as illustrated at 35 while its remaining extremity is pivotally connected to the link 36 which may be actuated in any suitable manner depending entirely upon the elevation of the apparatus.

In a construction as set forth, I am able to deflect a fluid in its most advantageous direction toward the vanes of the propeller and to accurately regulate the amount of fluid passing by a single operation of the control mechanism. The control mechanism is composed of very few parts and in a very slight movement is capable of simultaneously controlling the flow of fluid by all of the deflectors. Another advantage of my arrangements is that I minimize the number of parts necessary to actuate an electric generator from a propeller.

It is to be understood that while all of the several features of my improved machine have special coöperation with one another and together constitute a particularly effective mechanism for the purpose in view, certain of these features may be applied in other relations, and I therefore desire to cover the combination present in the several parts of my improved machine, whether complete in the general combination shown,

or elsewhere. I wish it to be understood that I use certain terms herein in a broad or generic sense such as by the word fluid I wish to include any substance capable of flowing.

What I claim is:

1. In a fluid motor, a pair of spaced fluid confining elements, one of said elements formed with an aperture, a propeller rotatably mounted between said elements in proximity to said aperture, a plurality of deflectors disposed in an annular row around said propeller, said deflectors having mountings whereby they are adapted for automatic swinging movement from an open to a closed position, whereby fluid entering between the deflectors on any side will be forced by automatic closure of the deflectors on the other side to escape through said aperture, and means for regulating flow of fluid from said aperture, whereby the power developed by the motor may be controlled.

2. In a fluid motor, a pair of spaced plates, one of said plates formed with an aperture; a propeller rotatably mounted between said plates adjacent said aperture, a plurality of deflectors disposed in an annular row around said propeller, whereby fluid entering between the plates will be directed to rotate the propeller, pivotal mountings for said deflectors whereby the deflectors are adapted for automatic movement from an open position on the side toward the flow of fluid to a closed position on the side away from the flow of fluid whereby the flow of fluid from the propeller is obstructed, to cause the fluid to escape through said aperture, and means for regulating the flow of fluid from the aperture.

3. In a fluid motor, a pair of spaced plates, one of said plates formed with an aperture; a propeller rotatably mounted between said plates adjacent said aperture, a plurality of deflectors disposed in an annular row around said propeller, whereby fluid entering between the plates will be directed to rotate the propeller, pivotal mountings for said deflectors whereby the deflectors are adapted for automatic movement to a position wherein the flow of fluid from the propeller is obstructed, to cause the fluid to escape through said aperture, said motor having a frame structure extending in proximity to said aperture, a flexible element having an inner portion attached to said frame structure, a rigid outer edge for said flexible element, and means whereby said rigid outer edge is adapted for movement toward and away from said aperture to regulate the flow of fluid from the aperture.

4. The combination with a fluid motor having a casing formed with an aperture

for escape of fluid, of a frame structure having a portion spaced apart from said casing in line with said aperture, an annular flexible element having the inner edge attached 5 to said frame portion, a ring attached to the outer edge of said flexible element, and means connected to said ring whereby it may be moved toward and away from the portions of said casing adjacent said aper-

ture to cause said flexible element to obstruct said aperture to a desired degree.

In testimony whereof I affix my signature in presence of two witnesses.

EDWARD J. GALLAGHER.
